UNITED STATES PATENT OFFICE.

FRANK P. GARDNER, OF BOSTON, MASSACHUSETTS.

NEEDLE-GUARD ATTACHMENT FOR SEWING-MACHINES.

1,307,295.

Specification of Letters Patent. Patented June 17, 1919.

Application filed August 9, 1918. Serial No. 249,201.

To all whom it may concern:

Be it known that I, FRANK P. GARDNER, a citizen of the United States, residing at Boston, county of Suffolk, State of Massachusetts, have invented a certain new and useful Improvement in Needle-Guard Attachments for Sewing-Machines, of which the following is a specification, reference being had therein to the accompanying drawings.

10 The invention relates to a needle guard attachment for sewing machines to protect the fingers of the operator against being injured by the needle during the operation of the machine. It is obvious that while the needle 15 is unguarded there is danger that the careless operator while feeding the work may allow his fingers to come into the path of movement of the needle and be severely injured.

20 In some of the needle guard attachments heretofore used the guard has obstructed the view of the work and it has been necessary to remove the guard in order to thread the needle. One object of the present invention 25 is to so construct and attach the guard that the operator shall be able at all times to see the work and also to enable him to thread the needle conveniently without removing the guard.

30 It is a rule of many insurance companies, especially of the employers' liability and accident insurance companies, that machines shall be provided with needle guards. The operatives, however, frequently object to the 35 use of needle guards because they think that it interferes with the speed of their work. Also sometimes in some factories the operatives are held responsible for the needle guard and either have to supply their own 40 needle guard or pay for it if it is lost so that whenever the factory is shut down at noon or at night the operative removes the needle guard and carries it away with him and because of the time required of putting it on 45 and taking it off the operatives often times leave the guard off while they are working if they think they can do so without being detected and then if they see the foreman or superintendent approaching they put it on 50 again if it can be quickly done. There is an objection to having the needle guard formed as a permanent part of the presser foot and on the other hand for the reasons above mentioned it is objectionable to so construct the 55 needle guard that it can be too readily at-

tached or detached by means of the ordinary tools within the reach of the operative. One object of the present invention is to construct and attach the needle guard in such manner that while it is a separate member from the 60 presser foot and can be attached by the use of proper tools, yet cannot be readily detached and replaced by use of the ordinary tools within the reach of the sewing machine operative. 65

The invention will be fully understood from the following description when taken in connection with the accompanying drawings and the novel features thereof will be pointed out and clearly defined in the claims 70 at the close of this specification.

In the drawings, Figure 1 is a perspective view of a portion of the working parts of a sewing machine showing the needle and needle bar, the presser foot and presser foot bar 75 and my improved form of needle guard attached to the presser foot, the needle being shown in its uppermost position.

Fig. 2 is a side elevation of the presser foot and needle guard attached thereto 80 viewed from the right hand side of the machine.

Fig. 3 is a rear view of the presser foot and needle guard attachment.

Fig. 4 is a front view of the needle guard 85 attachment detached from the presser foot.

Fig. 5 is a side elevation of the needle guard attachment detached, viewed from the left hand side and with one of the flange clamping fingers spread out as it is before 90 being attached to the presser foot.

Fig. 6 is a horizontal section on line 6—6 of Fig. 1.

Fig. 7 is a section on line 7—7 of Fig. 5.

Fig. 8 is a perspective view of the needle 95 guard attachment before it is attached to the presser foot.

Referring now to the drawings, 1 represents the head of a sewing machine, 2 the needle guard and 3 the needle connected 100 therewith in well known manner. 4 represents the presser foot bar, 10 the presser foot and 5 the presser foot shank which is formed with a vertical groove 6 in one side between the flange portions 11 and 36 to receive the 105 shank 7 of the presser foot bar and is formed with an open slot 8 in the upper end through which a screw 9 extends to clamp the presser foot to the shank 7 of the bar 4.

The upwardly extending shank 5 of the 110

presser foot has a flange portion 11 which toward its upper end forms one wall of the groove 6 and which as clearly shown in Fig. 2 tapers upwardly. The flange portion 12 5 on the opposite side of the presser foot shank preferably tapers downwardly as shown in Fig. 1 so that the two opposite flanges 11, 12 taper in opposite directions.

- The needle guard attachment is stamped 10 out of a single sheet of steel, preferably cold rolled steel, case hardened and blued. It is of skeleton form having a back portion 13 out of one side of which is stamped one of the back clamping wing portions 14. The 15 left hand side of the guard has stamped out of the same the other rear clamping wing portion 15, the unnecessary portions being cut away after the clamping wing is stamped out, thus leaving the left hand side of the 20 guard of skeleton form having an upper guard rail portion 16, a lower guard rail portion 17 and a front end connecting loop portion 18 which is bent around toward the front as shown in the drawings. The open 25 space 19 left in the side guard between the upper and lower members 16, 17, the front end loop 18 and the back 13 is not sufficiently large to cause any danger of the finger of the operative passing through the same to 30 get into the path of the needle, but it is sufficiently open to afford an unobstructed view of the work on that side.

The right hand side of the needle guard 35 has a slot 20 formed therein by cutting away the metal, thus giving a somewhat U-shape to the walls of said slot as clearly shown in Figs. 1 and 2. It also has a slot 21 in the rear part thereof which is formed when the right hand rear clamping arm 14 is 40 stamped out, said slot being partly in the rear portion of the needle guard and partly in the right hand side portion as is shown in Fig. 1.

The forward part of the right hand side 45 of the finger guard is formed with another cut out portion 22 thus giving an additional skeleton formation to the device. The forward portion 23 of the right hand side member of the needle guard is bent around forward thus forming a front bowed portion which extends toward the bowed portion 18 50 of the left hand side member as shown in Fig. 4, the two bowed portions 23 and 18 being spaced apart from each other enough 55 to afford a clear view between them yet not sufficient to permit the finger to be accidentally introduced into a dangerous position with relation to the needle.

The needle guard in its finished form 60 before it is attached to the presser foot is shaped as shown in cross section in Fig. 7 and in perspective in Fig. 8 with the wing 15 extending straight out at right angles to the back 13. The opposite wing 14 has the 65 portion adjacent the back 13 bent at right

angles to the back 13 and its end portion 141 bent at right angles to the portion 14 and extending toward the wing 15 as shown in Fig. 7. The distance between the wing 14 and the wing 15 is equal to the width of the presser foot shank 5 so that the socket formed by the wings 14 and 15 and back 13 of the guard may be inserted down over the top of the tapered shank of the presser foot, the two wings forming ways for the two opposite sides of the presser foot shank. As already stated the flange 11 of the presser foot shank tapers upwardly, that is, increases in thickness downwardly although it is of uniform width. To correspond with this taper the plane of the turned end portion 141 of the wing 14 flares downwardly away from the plane of the back 13 so that the passage 24 between the back 13 and the said turned portion 141 increases in width from the top to the bottom at a corresponding angle of taper to that of the tapered flange 11. When the guard is inserted over the top of the presser foot shank it will slide down until it comes to a point where the wedge shaped flange 11 is equal in thickness to the tapered passage 24 and it can go no farther down. Then the outer portion 151 of the flange 15 is bent around against the back side of the reversely tapered flange 95 portion 12 of the shank and presser foot as shown in Fig. 6. Now on account of the upward thickening of the flange 12 it is impossible to pull the needle guard up away from the presser foot because it will be wedged in by the upward swelling of the shank portion 12. Neither can the needle guard be pushed down any farther because it has already been pushed down as far as it can go by reason of the wedging action of the flange 11 within the upwardly tapered way 24. The needle guard, therefore, is securely clamped to the presser foot without the aid of screws or any exterior fastening means, even before the presser foot 110 is assembled with the presser foot bar 4. After it is assembled with the presser foot bar by means of the screw 9 it is still more difficult to detach the needle guard from the presser foot. It can not be detached 115 even by straightening out the wing 15 again into the position shown in Fig. 7, assuming that such straightening out could be done. Such straightening out, however, would weaken the wing and it could not be 120 done more than once or twice at the most before it would break the wing in two.

Preferably the end portion 151 of the wing 15 which bends around behind the presser foot is somewhat narrower than the body of the wing 15 as shown in Fig. 2, the body of the wing 15 being left the full width of the portion which is struck out of the side guard and equal to the height of the space between the upper rim 16 and the 130

lower rim 17 of said side portion of the needle guard for the purpose of giving as much strength as possible to the wing. The bent back portion 151 however is made narrower 5 so that it can be more easily bent and more easily fit itself to the sloping rear face of the shank of the presser bar.

The shoulder 25 will serve as a stop for the upward movement of the guard after 10 the wing 15 is bent into clamping position even if the flange 12 is not tapered below the wing.

The right hand side of the guard, that is the side portion which is on the same side 15 as the short toe 26 of the presser foot has a bow 27 which extends down lower than the lower rim 17 of the other side of the guard to give more effectual protection on that side which is more exposed by reason 20 of the short toe.

The point of the needle is thus guarded throughout its entire stroke.

What I claim is:

1. A needle guard attachment for a presser foot having a shank with a tapered wedged 25 shaped flange, said guard attachment having a guard portion which substantially surrounds the path of movement of the needle and having wings integral with said guard 30 portion for clamping the guard to the presser foot, one of said wings being bent to form a tapered passage to receive one of the flanges on the shank of the presser foot and another wing which is capable of being 35 bent around against the back of the other flange of the shank of the presser foot.

2. A needle guard attachment for a presser foot having a shank formed with reversely tapered side flanges, said needle guard attachment 40 having a guard portion which substantially surrounds the path of movement of the needle and having wings integral with said guard for clamping the guard to the presser foot, one of said wings being 45 bent to form a tapered passage to receive one of the tapering flanges on the shank of the presser foot and another wing which is capable of being bent around the edge of the reversely tapered flange of the presser foot.

3. A needle guard attachment for a presser foot having a shank formed with reversely tapered flanges on two opposite side edges, said guard attachment having a guard 55 portion which substantially surrounds the path of movement of the needle, said guard being formed out of sheet metal and having wings struck out of the body of said guard portion, one of said wings being bent to form 60 a tapered passage to receive one of the tapering flanges on the shank of the presser foot and another wing which is capable of being bent around the other tapered flange of the shank of the presser foot and clamped 65 against the back side thereof.

4. A needle guard attachment for a presser foot having a shank formed with two opposite side flanges, said guard attachment having a guard portion which substantially surrounds the path of movement of the needle 70 and having two wings integral with said guard for clamping the guard to the presser foot shank, one of said wings being bent to form a tapered passage corresponding in angle of taper to the downwardly tapered 75 flange of the presser foot shank and another wing being capable of being bent around the edge and against the back of the other flange of the presser foot shank, said other flange being formed with a thickened portion above 80 said wing which forms a stop for the upward movement of the guard after it is clamped to the presser foot shank and the increasing thickness downward of the first flange forming a stop to limit the downward movement 85 of the guard after it is clamped.

5. A needle guard attachment for a presser foot formed out of sheet metal having two wings struck up out of the body by which the guard may be attached to a presser foot 90 shank, one of said wings being bent to form a vertical groove tapered from the lower end upward to receive a correspondingly tapered flange on the shank of a presser foot, the other of said wings being capable of being 95 bent around the opposite side of the presser foot shank after it has been inserted in said groove of the first wing, said guard being formed with a rear portion, and two forwardly projecting side portions out of which 100 said wings are struck, the forward ends of said side portions being turned in toward each other in front of the path of movement of the needle.

6. In combination with a presser foot having a shank formed with a tapered wedge shaped flange, a needle guard attachment therefor having a guard portion which substantially surrounds the path of movement of the needle and having wings integral 110 with said guard portion for clamping the guard to the presser foot, one of said wings being bent to form a tapered passage to receive one of the flanges on the shank of the presser foot and another of said wings being 115 bent around against the back of the other flange of the shank of the presser foot.

7. In combination with a presser foot having a shank formed with opposite side flanges reversely tapered, a needle guard attachment therefor having a guard portion which substantially surrounds the path of movement of the needle and having wings integral with said guard for clamping the guard to the presser foot, one of said wings 120 being bent to form a tapered passage to receive one of the tapering flanges on the shank of the presser foot and another of said wings being bent around the edge of the reversely tapered flange of the presser foot. 125 130

8. In combination with a presser foot having a shank formed with opposite side flanges reversely tapered, a needle guard attachment therefor having a guard portion which substantially surrounds the path of movement of the needle, said guard being formed out of sheet metal and having wings struck out of the body of said guard portion, one of said wings being bent to form a tapered passage to receive one of the tapering flanges on the shank of the presser foot and another of said wings being bent around the other tapered flange of the shank of the presser foot and clamped against the back side thereof.
9. In combination with a presser foot having a shank formed with two opposite side flanges, one of which tapers downwardly, a needle guard attachment therefor, said guard attachment having a guard portion which substantially surrounds the path of movement of the needle and having two wings integral with said guard for clamping the guard to the presser foot shank, one of said wings being bent to form a tapered passage corresponding in angle of taper to the downwardly tapered flange of the presser foot shank and the other wing being bent around the edge and against the back of the other flange of the presser foot shank, said other flange being formed with a thickened portion above said wing which forms a stop for the upward movement of the guard after it is clamped to the presser foot shank, the increasing thickness downward of the first

flange forming a stop to limit the downward movement of the guard after it is clamped.

10. In combination with a presser foot having a shank formed with two opposite side flanges, one of which tapers downwardly, a needle guard attachment therefor, said guard attachment being formed out of sheet metal having two wings struck up out of the body by which the guard may be attached to a presser foot shank, one of said wings being bent to form a vertical groove tapered from the lower end upward to receive a correspondingly tapered flange on the shank of a presser foot, the other of said wings being capable of being bent around the opposite side of the presser foot shank after it has been inserted in said groove of the first wing, said guard being formed with a rear portion and two forwardly projecting side portions out of which said wings are struck, the forward ends of said side portions being turned in toward each other in front of the path of movement of the needle.

11. A presser foot for a sewing machine having a shank formed with two opposite vertical side flanges reversely tapered, one of said flanges tapering upwardly and the other tapering downwardly, in combination with a needle guard having two opposite side portions shaped to form reversely tapered passages with which said tapered flanges engage.

In testimony whereof I affix my signature.

FRANK P. GARDNER.
